DEHUMIDIFIER

Harry E. Thompson, Steubenville, Ohio, assignor
to The Ohio Foundry & Manufacturing Com-
pany, Steubenville, Ohio, a corporation of Ohio

Application August 17, 1953, Serial No. 26,481

Term of patent 14 years

(Cl. D16—2)

To all whom it may concern:

Be it known that I, Harry E. Thompson, a citizen of the United States, residing at Steubenville, in the county of Jefferson and State of Ohio, have invented a new, original, and ornamental Design for Dehumidifiers, of which the following is a specification, reference being had to the accompanying drawing, forming part thereof.

Figure 1 is a perspective view showing the top, front and one side of a dehumidifier embodying my new design;

Figure 2 is a rear elevation; and

Figure 3 is a top plan view thereof.
The other side not shown is like the side shown.
I claim:
The ornamental design for a dehumidifier, as shown and described.

HARRY E. THOMPSON.
